UNITED STATES PATENT OFFICE

2,670,981

LATCH MECHANISM

Douglas L. Wenham, Hamilton, Auckland,
New Zealand

Application January 31, 1952, Serial No. 269,196

2 Claims. (Cl. 292—114)

1

The invention relates to catches for doors and the like, of the type commonly known as "flush" catches, wherein a control member is normally held by spring pressure in an outer position so that the catch will keep the door, or the like closed, and the control member is adapted to be pressed inwards by finger pressure against the spring resistance to release the catch and to make available a recess which can be gripped by the finger to open the door, or the like.

Although the invention has been devised principally for use with doors, it can be used for other purposes, for example for keeping drawers or the like closed, and facilitating opening of the same.

One object of the present invention is to provide a catch of the above type which is easier to use than present catches of the said type.

In one aspect the invention consists in a catch of the type described, for a door or the like, wherein the control member is bodily slideable inwards to disengage the catch and the construction is such that any side of the recess can then be gripped by a finger to enable the door, or the like to be pulled open.

Another object of the invention is to provide a catch of the above type which is simpler to fit than present catches of the said type.

In a further aspect, therefore, the invention consists in a catch of the type described, for a door or the like, wherein the construction is such that only one round hole is required through the door, or the like to enable the part of the catch mechanism associated with the door or the like to be secured in position.

In a still further aspect, the invention consists in a catch of the type described, for a door, or the like comprising a housing adapted to be inserted through a hole in the door, or the like and to be conveniently secured therein, the control member being suitably retained in said housing and having a press-button part by which it is conveniently slideable bodily inwards in the housing against the spring resistance, and a hook part projecting beyond the inner end of the housing, and a separate co-acting member adapted to be mounted to the frame or cabinet or the like adjacent to the door or the like and to be operatively engaged by the hook part to hold the door or the like closed when desired, the control member in its outer position being rockable in the housing against the spring resistance to allow the hook part to snap over the co-acting member with closing of the door or

2

the like and guiding means being associated with the housing to guide the movement of the control member so that when it is pressed inwards the hook part will move inwards and to one side so that the door or the like can be opened without the hook part fouling the co-acting member.

In its outer position the control member is preferably held against excessive outward movement by means of an inwardly projecting lip formed in the housing and the lip is preferably provided all around the recess to provide a finger grip available from any side of the recess for opening the door or the like.

20 A feature of the invention in its preferred form resides in the construction of the catch to prevent opening of the door or the like except upon an initial inward pressure and movement of the press-button part.

One form of the invention and a modified form of co-acting member will now be described with reference to the accompanying drawings.

In the drawings:

25 Figure 1 is a section on the line 1—1, Figure 2, through the catch and through a part of the door and frame with which the said catch is operatively associated, the control member being shown in its normal outer position,

Figure 2 is an elevation at right angles to Figure 1, showing the two principal parts of the catch in engagement,

Figure 3 is a section on the line 1—1 Figure 2, showing the control member in its inner position,

35 Figure 4 is a horizontal sectional view through a part of a door and a frame member adjacent thereto, showing the invention with a preferred form of co-acting member,

Figure 5 is a side elevation of the co-acting member shown in Figure 4, and

Figure 6 is a front elevation showing the co-acting member or the underside of a shelf.

In the construction shown in the drawings, a housing 1 of cylindrical and tubular form is adapted to be inserted through a hole in the door or the like and has an outer peripheral flange 1a adapted to engage the outside of the door or the like, the inner end of the housing being threaded to receive a preferably knurled ring or nut 2 which engages an inner side of the door or of the front of the drawer or the like as the case may be, in order to secure the housing therein.

The inside of the housing is in the form of a 55 cylindrical chamber 3 with an inwardly pro-

jecting lip or flange $1b$ at the outer end and, at the inner end, internal threads to receive guiding means comprising a slotted retaining and guide member 4 which screws into the said inner end of the housing. The member 4 has a slot $4a$ adapted to guide the shank of a flat hook part $5a$ projecting beyond the inner end of the housing and forming part of a floating control member 5 which is slidably retained within the housing and which has at its outer end a press-button part $5b$ substantially flush with the outer end of the housing. The control member has an outwardly projecting flange $5c$ adapted to act with the lip or flange $1b$ of the housing to hold the control member against excessive outward movement so that the control member is normally held in the position as shown in Figure 1 by means of the compression spring 6 but is bodily slidably inwards in the housing against the spring resistance to disengage the catch.

The spring 6 is held in compression between the press-button part $5b$ of the control member and the slotted member 4 .

The hook part $5a$ is formed with a hook lip $5d$ adapted to engage a separate co-acting member 7 to be hereinafter described, and a cam face $5e$ on the shank of the hook part is adapted to engage guiding means comprising one end of the slot $4a$ so that when the control member is pushed inwardly the hook part will move at an angle inwards and to one side into the position shown in Figure 3, so that when the door or the like is opened the hook part $5a$ will not foul the member 7 . The upper edge of the said hook part is shaped as shown to permit the angular inward and side movement of the control member when the same is pressed inwards in the housing.

The co-acting member 7 is in the form of a disc $7a$ having a curved wall $7b$ projecting perpendicularly therefrom, with a lip $7c$ forming the outer end of the said wall so that the same will be securely engaged by the hook lip $5d$ of the hook part $5a$. The disc $7a$ is provided with holes to receive mounting screws $7d$ for mounting the co-acting member to the frame or cabinet or the like adjacent to the door or the like.

The alternative form of co-acting member shown in Figures 4 to 6 comprises a square wall 8 having a lip $8a$ formed along one edge, for engagement by the hook part, and with two flanges $8b$ and $8c$ projecting perpendicularly from two of its other edges, both flanges projecting at the same side of the wall 8 .

Each flange has a hole 9 and a slot $9a$ therein, to receive screws 10 for holding the co-acting member in position. The co-acting member can be mounted as shown in Figure 4, or alternatively it can be mounted as shown in Figure 6. The latter mounting can be used when the co-acting member is mounted below a shelf, whereupon the vertical disposition of the lip $8a$ allows for a limited vertical sagging of the shelf without affecting engagement of the hook part with the co-acting member.

With both methods of mounting, the flange not used for securing the co-acting member in position acts as a brace for the wall 8 .

In operation, when the door or the like is closed, with either of the forms of co-acting member shown in the drawings, the hook part $5a$ is engaged over the lip $7c$ or $8a$, the shank part at $5e$ being so designed and associated with the end of the slot $4a$ that when the catch is closed with the hook part properly engaged with the co-acting member the door or the like cannot

open except upon an initial inward pressure and movement being applied to the press-button part.

When the press-button part of the control member is pressed inwards as is shown in Figure 3 of the drawings, the control member slides bodily inwards and to one side to disengage the co-acting member, due to the engagement of the cam face $5e$ with the end of the slot $4a$. The lip or flange $1b$ in the housing is made available all around the said housing due to the bodily inward movement of the control member, so that the finger can engage the said lip or flange conveniently from any desired angle, i. e. from any side of the recess, for the purpose of enabling the door or the like to be pulled open.

The control member in its outer position is rockable in the housing against the spring resistance to allow the hook part to snap over the co-acting member, the slot in the member 4 being designed to allow said rocking.

The catch may be made of metal or of any suitable plastic or of any desired combination of the two, or of any other suitable material.

A feature of the invention is its simplicity in that it requires only one round hole to be drilled in the door or the like for either vertical or horizontal opening of the said door or the like. Also the attachment to the door or the like by a ring or nut 2 obviates the necessity for any visible screws outside the door or the like.

Claim:

1. A latch mechanism for a closure member comprising a housing having a flange at one end and a guide member secured in the other end of the housing, a control member movably mounted in the housing having a press button portion at one end and a hook member at the other end with a cam face between the two ends, said control member being movable so that the press button portion is movable toward and away from the flange and the control member is partially retractable into and advanceable from the housing at the guide member end of the housing, said button portion of the control member having a shoulder portion adapted to contact the flange to limit the movement of the control member in the direction toward the flange, and a spring mounted around the control member abutting at one end thereof against the guide member and the other end against the press button portion, said press button of the control member being adapted to be pushed inwardly in a direction away from the flange by a finger of the operator toward the guide member so that the cam face of the control member will contact the guide member to deflect the hook member to releasing position with the finger of the operator positioned between the flange and the press button portion whereby the finger engages the flange to open the closure member.

2. A latch mechanism for a closure member comprising a housing having an inwardly projecting flange at one end and a guide member in screw threaded contact at the other end of the housing, a control member movably mounted in the housing having a press button portion at one end and a hook member at the other end with a cam surface between the press button portion and hook member, said press button portion being adapted to contact the flange to limit the movement of the control member in the direction toward the flange, and means to urge the control member toward the flange, said control member being movable so that the press button

portion is movable toward and away from the flange and the control member is partially retractable into and advanceable from the housing at the guide member end of the housing, said press button portion of the control member being adapted to be pushed inwardly by a finger of the operator in a direction toward the guide member so that the cam surface of the control member will contact the guide member to deflect the hook member to releasing position with the finger of the operator positioned between the flange and the press button portion whereby the finger engages the flange to open the closure member.

D. L. WENHAM.
